UNITED STATES PATENT OFFICE.

PERRY C. WOODS, OF WASHINGTON, IOWA.

INTERNAL-COMBUSTION ENGINE.

1,323,139.

Specification of Letters Patent.

Patented Nov. 25, 1919.

Application filed December 13, 1916. Serial No. 136,666.

To all whom it may concern:

Be it known that I, PERRY C. Woods, a citizen of the United States, residing at Washington, in the county of Washington 5 and State of Iowa, have invented certain new and useful Improvements in Internal-Combustion Engines; and I do hereby declare the following to be a full, clear, and exact description of the invention, such as 10 will enable others skilled in the art to which it appertains to make and use the same.

This invention relates to improvements in internal combustion engines, and has for its object to provide an improved engine in 15 which the compressed charge in the working cylinder is ignited by the combustion of fuel in an auxiliary high pressure cylinder.

Another object is the provision of a novel valve structure for controlling the discharge 20 of the combustion from the high pressure cylinder to the working cylinder.

With these and other objects in view, the invention consists in the novel construction, combination and arrangement of parts as 25 will be hereinafter specifically described, claimed and illustrated in the accompanying drawings, in which:

Figure 1 represents a side elevation, partly in section, of the improved engine. 30 Fig. 2 represents a front elevation thereof, partly broken away.

Fig. 3 represents an enlarged sectional view through the cylinder of the engine.

Fig. 4 represents a transverse sectional 35 view through the head of the cylinder.

Referring to the drawings in detail, wherein similar reference numerals designate corresponding parts throughout the several views, the numeral 5 indicates a 40 main or working cylinder of the engine, which is preferably of the double walled type, providing the water chamber 6, by which the engine is cooled during operation. The piston 7 is reciprocably mounted in the 45 cylinder 5 and is connected with a piston rod 8 which is pivotally connected at 9 to the connecting rod 10. The terminal of the connecting rod 10 opposite the piston 7 is connected with the crank pin 11 of the crank 50 shaft 12, which latter is supported in suitable bearings.

The head of the cylinder 5 is formed with an exhaust port in which is arranged an exhaust valve 6^a, which may be operated by 55 any approved type of valve operating mechanism (not shown). The head is also

provided with an inlet port 13, which is restricted adjacent its outer terminal to present an inclined valve seat 15, with which is engaged the inlet valve 16. An auxiliary 60 or high pressure cylinder 17 is formed integral with the working cylinder 5 and is of considerably less internal diameter than the cylinder 5. A piston 18 is reciprocably mounted in the cylinder 17 and is connected 65 with a rod 19, having pivotal connection at 20 with the angular terminal 21 of an arm 22, rigidly connected with the connecting rod 10 of the main piston 7.

The upper end or combustion chamber of 70 the cylinder 17 communicates with the inlet port 13 by a tapered port 23, forming a seat for the tapered terminal of a needle valve 24, which is slidably mounted in the head of 75 the cylinder.

A rocker arm 25 is pivotally secured to a supporting bracket 26 attached to the cylinder 5, and is engaged at one end with the upper terminal of the needle valve 24 and at its opposite end with a push rod 27, slidably supported in guides 27^a and engaged 80 at its lower terminal with a cam 28 carried by the crank shaft 12.

In operation, the explosive mixture is drawn into the cylinders 5 and 17 through 85 the ports 13 and 23, during the suction stroke of the pistons 7 and 18, and during the subsequent compression stroke the charge is compressed. During the compression stroke of the high pressure piston 18 the 90 needle valve 24 is retained in closed position by the cam 28 operating upon the rod 27 and rocker arm 25. During the compression stroke of the high pressure piston 18 the mixture contained in the explosion chamber 95 thereof is compressed to such a degree that the mixture is ignited and the fire from the explosion is directed through the ports 23 and 13 and into the main cylinder 5, where it ignites the compressed charge in the main 100 cylinder operating the piston 7. It will be understood that the needle valve 24 is automatically released by the cam 28 at the time of the explosion of the charge in the high pressure cylinder 17 and the force of the explosion 105 automatically opens the valve 24.

What I claim is:

An internal combustion engine including a main cylinder having intake and exhaust ports and a piston provided with a piston 110 rod operable within the main cylinder, means controlling said ports, an auxiliary

cylinder formed on the main cylinder and having a port communicating with the inlet port, a piston operable in said auxiliary cylinder, a piston rod for said second mentioned piston, a connecting rod pivoted to the piston rod of the first named piston and adapted to be connected to a crank shaft, a substantially L-shaped arm formed on the connecting rod and pivoted to the piston rod

of the second named piston, and a needle valve adapted to control the ports from the auxiliary cylinder to the intake port.

In testimony whereof I affix my signature in presence of two witnesses.

PERRY C. WOODS.
